UNITED STATES PATENT OFFICE

EDWARD B. SWIFT, OF SEATTLE, WASHINGTON

ANCHOR

Application filed December 26, 1929. Serial No. 416,536.

My invention relates to improvements in anchors for marine use and the object of my invention is to improve the construction and increase the efficiency of anchors of this nature and to provide an anchor which will have a greater holding capacity in proportion to the weight of the anchor.

Another object is to provide an anchor of this nature which is less liable to be moved by a slow, step by step, movement commonly called walking of the anchor.

A further object is to provide anchor means in which more than one anchor member is carried on a single anchor stock and in which the weight is thus more evenly distributed throughout the length of the stock so that the anchor will have a greater holding power in proportion to its weight.

Another object is to provide a simple and efficient way for increasing the weight of old anchors which are already in use by securing an additional or secondary anchor member onto the stock of the said old anchor.

Other and more specific objects will be apparent from the following description taken in connection with the accompanying drawings.

Anchors of the so-called star or mushroom type are extensively used for anchoring floating fish traps of the form used in Alaskan waters for catching salmon and other salt water fish. These anchors are usually large and heavy and often weigh as much as six tons. These anchors are required to hold the heavy floating traps in the same locations for long periods of time, often in rough weather, and it has been found that where a star or mushroom anchor is placed on the rear end of a stock of substantial length there will often be a tendency for the anchor to move or to walk due to the pull on the line veering slightly from side to side or due to raising and lowering of the forward end of the anchor stock.

In accordance with my invention, I provide

an additional anchor member on the forward end of the anchor stock which holds the forward end of the stock down and prevents lifting and sidewise movement of the same, thus allowing the rear anchor to hold with greater efficiency so that walking of the anchor is prevented.

In the accompanying drawings, Figure 1 is a view partly in side elevation and partly in section of an anchor constructed in accordance with my invention.

Fig. 2 is an end elevation of the same.

Fig. 3 is a view similar to Fig. 1 with the anchor stock and rear anchor member broken away.

Fig. 4 is an end elevation of the device shown in Fig. 3.

Fig. 5 is a view similar to Fig. 1 except that the larger anchor is shown at the forward end of the stock and the smaller anchor is shown at the rear end to thereby cause the anchor stock to assume an upward incline from rear to front end when the anchors rest on the ground.

Fig. 6 is a longitudinal sectional view of a one piece duplex anchor constructed in accordance with my invention.

Fig. 7 is a front elevation of the anchor shown in Fig. 6.

Fig. 8 is a fragmentary view partly in elevation and partly in section showing the front end of an anchor stock which has a weight secured thereon for holding said front end of the anchor stock down.

Fig. 9 is a view in side elevation, with parts in section, of a duplex anchor in which the anchor line is connected with the anchor stock between the two anchors.

Fig. 10 is a view partly in side elevation and partly in section of an anchor stock having three anchors thereon.

Fig. 11, is a side elevation with parts in section of a duplex anchor, showing the anchor stock made in two parts which are flexibly linked or connected together.

Fig. 12 is an elevation of a modified form of anchor in which the anchor member is provided near the front end of the stock and the rear end of the stock is made large and heavy to hold the anchor member down.

Fig. 13 is an end elevation of a star anchor which is generally irregular in shape.

Fig. 14 is an elevation of a modified form of anchor member in the nature of a cross arm for the front end of an anchor stock.

Referring to Figs. 1 and 2, I show an anchor stock 15 having a larger star shaped anchor 16 seated on an expanding portion 17 at the rear end of the stock and secured thereon by means of a clamp 18. Another anchor 19 is seated on a taper 20 near the front end of the stock and secured thereon by means of a clamp 21. Keys 22 may be used to prevent rotary movement of anchors 16 and 19 on the stock. A line or cable 23 is secured to the forward end of the stock. The anchors 16 and 17 are shown as six point star type anchors but they may be of various other forms as shown in succeeding figures, or may have any number of points.

In Figs. 3 and 4 I show a mushroom shaped anchor 24 mounted on the forward end of an anchor stock 15, it being understood that the stock has another anchor mounted on its rear end. The anchor 24 may be left free and rotatable on the shank, as shown, or it may be keyed thereto in the same manner as the anchors 16 and 19.

In Fig. 5 I have shown a smaller anchor 25 mounted on the rear end of an anchor stock 15 and a larger anchor 26 mounted on the forward end of said anchor stock. This allows the anchor stock to assume an upward incline from rear to front end, which incline may correspond to the general of pull of an anchor line or cable 27. This makes it possible to allow the anchor line to pull upward at a greater angle relative to the horizontal without lifting the forward end of the stock than would otherwise be possible, thus making it possible to use less anchor line with this type of anchor.

In Figs. 6 and 7 I have shown a duplex anchor of one piece construction embodying a rear anchor 28 and a front anchor member 29. These anchors are each shown to be of four point construction but may have more or less points if desired. The construction of this anchor member is essentially strong and heavy throughout and the front end of the anchor is preferably more massive than the rear end of the same. A short shank 30 is provided on the front end to which an anchor line may be secured.

In Fig. 8 I show the front end of an anchor stock 15 as provided with a weight 31 to hold the front end of the stock down when a pull is exerted thereon. This weight 31 is not an anchor itself but serves to increase the efficiency of the anchor not shown, on the rear

end of the stock by holding the stock down.

In Fig. 9 I show a duplex anchor constructed in which an anchor line 32 is connected with an anchor stock 15 between two anchors 33 and 34. The connection is preferably made by a clip or clamp 35 within which the anchor stock is free to rotate and said clip is preferably positioned closer to the front anchor than to the rear one.

Fig. 10 shows three anchors 36, 37 and 38 of gradually increasing size mounted on an anchor stock 15. These anchors may either increase in size from the rear to the front end of the stock, as shown, or they may be arranged in the reverse manner.

In Fig. 11, I show two anchors 39 and 40 mounted on separate pieces of stock 15' and 15" respectively, which pieces of stock are connected with each other by link means 41. In this construction the two anchors both operate to resist pull on the anchor line but said anchors are more free to assume different inclinations and positions on rocky bottoms than when they are both secured to one solid anchor stock.

Fig. 12 shows a modified form of the invention in which a single anchor member 42 is provided on a stock 43 and a relatively large heavy stock portion 44 extends rearwardly from the anchor member 42.

Fig. 13 shows the head of a star type anchor 45 which is not a true star but may be a generally elliptical irregular shape with points projecting outwardly therefrom. This anchor head may be used in place of any of those hereinbefore described. On a sloping bottom it has less tendency to roll than a star anchor.

In Fig. 14, I show an anchor bar 45 which may be used on the front end of an anchor stock to furnish weight to hold the anchor stock down. This anchor bar is provided with flukes 47 at the ends which will engage with and dig into the ground or ocean bed thus offering resistance to a pull.

These anchors are all constructed so as to provide more weight on the forward end of the stock thus affording means for holding down the front end of the anchor stock which causes the anchor on the rear end of the stock to dig in more efficiently and which prevents walking movement of the rear anchor and which adds its holding power to that of the rear anchor.

An important use for this invention is found in rebuilding star anchors which are already in use and which have been found too light for the load they are intended to hold. In doing this I take the old anchor which is too light and place another anchor on the forward end of the anchor stock. When this is done I preferably replace the clamps 18 by rings 48, as shown in Figs. 3 and 4. These rings are secured to the anchor stock by set screws 49 which may be tightened

into punch marks or indentations made in the anchor stock. This constitutes efficient means for securing the anchor to the stock by the use of the simplest tools which are always available.

The foregoing description and accompanying drawings clearly disclose a preferred embodiment of my invention but it will be understood that this disclosure is merely 10 illustrative and that such changes may be made as are fairly within the scope and spirit of the following claims.

I claim:

1. In an anchor, a stock, a star shaped anchor member adjacent each end of said stock, 15 said anchor members being of different size, both of said anchor members being dished on the side toward the same end of said stock and a line connected with the end of said 20 stock toward which said anchor members are dished.

2. In an anchor, a stock, a star shaped anchor member on the rear end of said stock, means for securing an anchor line to the 25 front end of said stock, and another star shaped anchor member on said stock adjacent the front end, but to the rear of said line securing means, said two anchor members being dished in the same direction and 30 each of said star shaped anchor members having three or more points whereby two or more points of each anchor member will engage the ground at one time.

3. In an anchor, a stock, a star anchor 35 member on the rear end of said stock, another star anchor member on the forward end of said stock, and an anchor line connected with the forward end of said stock in front of said last named anchor member, both of said anchor members being concave on the side toward the front end of said stock.

4. An anchor embodying two multiple point star anchor members disposed in spaced apart relation and rigidly connected together, the foremost anchor member being 45 smaller than the rearmost anchor member, and means for connecting an anchor line with the foremost of said anchor members.

5. In an anchor, a stock, and two star 50 shaped anchor members secured to said stock adjacent the opposite ends thereof, the foremost one of said anchor members being of larger size than the other.

6. In an anchor member, a stock, an anchor line connected with the front end of said stock, a smaller star shaped anchor member secured to the rear end of said stock, and a larger star shaped anchor member secured to the forward end of said stock, said two 60 anchor members normally serving to support said stock in an upwardly inclined position from rear to front end.

7. An anchor embodying two multiple point dish like star shaped anchor members 65 disposed in spaced apart relation and rigidly

connected together the anchor member at the foremost end being heavier than the anchor member at the rear end and means for connecting an anchor line with said foremost anchor member.

8. In an anchor member, a plurality of stock sections, means flexibly connecting the ends of said stock sections and a star shaped anchor member on each said stock sections.

In testimony whereof I affix my signature. 75
EDWARD B. SWIFT.
